US0D1059266S

(12) **United States Design Patent** (10) Patent No.: **US D1,059,266 S**
(45) Date of Patent: ** Jan. 28, 2025

(54) **BATTERY FOR CAR REFRIGERATOR**

(71) Applicant: **GUANGZHOU ISSYZONE TECHNOLOGY CO., LIMITED**,
Guangdong (CN)

(72) Inventors: **Taiping Yang**, Guangdong (CN);
Zhousheng Yang, Guangdong (CN)

(73) Assignee: **GUANGZHOU ISSYZONE TECHNOLOGY CO., LIMITED**,
Guangdong (CN)

(**) Term: **15 Years**

(21) Appl. No.: **29/883,774**

(22) Filed: **Feb. 3, 2023**

(51) LOC (15) Cl. **13-02**

(52) U.S. Cl.

USPC **D13/103**

(57) **CLAIM**

The ornamental design for a battery for car refrigerator as shown and described.

DESCRIPTION

FIG. 1 is a perspective view of a battery for car refrigerator showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines illustrate portions of the battery for car refrigerator that form no part of the claimed design. The dot-dash broken lines define the bounds of the claimed design and form no part thereof.

1 Claim, 8 Drawing Sheets
